SHOE WITH INTERCHANGEABLE HEELS

Guillermo Staines, Mexico, D. F., Mexico, assignor to Auguste Daumas, Mexico, Mexico

Application June 28, 1934, Serial No. 732,930
In Mexico July 8, 1933

2 Claims. (Cl. 36—34)

The invention refers to a shoe having a heel plate especially adapted to provide means for securing interchangeable heels to ladies' shoes. The invention has for its principal object to provide 5 easily installed and rigid means for permitting interchange of the heels of the shoes for other heels with different outside covering, of different color or shape, which is especially convenient and desirable with shoes made of variously colored 10 leather as heels of each of the colors may be given with each pair of shoes bought, and also for changing the heels from one shoe to the other, whereby the soles of the heels will be worn out more uniformly, preventing the fatigue of 15 the wearer occasioned by unevenly worn heels which let the foot strike the ground at an angle.

It is another object of the invention to provide a heel plate the under side of which has a convex shape corresponding with the concavity of 20 the upper part of the heel, whereby the heel plate forms a unitary structure with the heel when both are united by a screw, preventing any tendency of the heel to turn.

It is a further object of the invention to provide 25 a heel plate having means preventing it from being displaced with respect to the heel part of the shoe, such means comprising a projection on the under side of the plate passing through a hole in the sole, and sharp-edged raised ribs 30 extending from said projection for embedding themselves both into the material surrounding said hole and into the inner sole when the heel plate is tightened against the heel.

The invention has also for its object to provide, 35 by means of the aforesaid projection, a longer guide for the shaft of the screw uniting the plate and the heel, which prevents any lateral play of said screw and gives greater stability and strength to the union.

It is still another object of the invention to make the heel plate not of stamped sheet metal, but of solid cast metal or any other conventional cast or pressed material so as to give it a sufficient thickness to provide a relatively heavy rear 40 part shaped to receive the rounded heel of the foot, and a tapering front part terminating in a sharp front edge which does not form any bulge at the point of junction with the insole.

It is finally an object of the invention, to rigidly grip the rear end of the metal shank stiffener 45 existing in high-heeled ladies' shoes, between the metal heel plate and the heel portion of the shoe materials, preventing thereby any possibility of deforming the shoe by torsional stresses.

In the accompanying drawing:

Figure 1 is a sectional view of the rear part of a lady's shoe, showing the heel attached by the plate.

Figure 2 is a top view of the heel plate.

Figure 3 is a view from below of the heel plate. 5

Figure 4 is a front view of the heel plate.

Figure 5 is a cross-sectional view on the line a—a of Figure 3.

As appears from the drawing, the heel plate 1, preferably cast from a non-oxidizing metal 10 such as aluminum, is made to conform in its outlines with the heel portion of the insole of the shoe. The upper surface of said plate is slightly concave so as to snugly receive the heel of the foot, and its straight thin front edge is lightly 15 curved downwardly so as to embed itself in the insole of the shoe. The under side of the heel plate is convex on lines parallel with the concavity of the upper part of the heel. From the center of the under side of the heel plate projects a ring 2 having a straight center hole countersunk at the top and slightly conical outer walls. From this ring project several equally spaced vertical sharp-edged ribs 3, and other sharp-edged ribs 4 extend themselves from said 20 vertical ribs along the under side of the heel plate, some of these ribs being placed along the longitudinal axis of the plate and others at right angles to them.

The projecting ring 2 passes through a round 30 hole stamped through the insole 5 and the outer sole 6, the height of said projection being somewhat smaller than the thickness of both of these soles, so that the latter may be firmly compressed 35 when the plate 1 is screwed to the heel 7 by means of the wood screw 8. The sharp lateral ribs 3 cut into the leather surrounding the hole in the soles 5 and 6, and the longitudinal ribs 4 also embed themselves in the insole 5, preventing 40 the plate 1 from turning and sliding. When the heel 7 has been attached, the covering flap 9 of the insole 5 is laid on top of the plate 1, without any adhesive, so that it may be raised when the screw 8 is to be loosened, although this flap could also be glued to the plate 1, leaving only an opening 45 above the head of the screw 8. The metal shank stiffener 10 used for holding the shape of high-heeled shoes and located between the outer and the inner sole, is firmly gripped with its rear end between the insole and plate 1, and the outer sole and the heel 7, giving it therefore a much firmer hold than if the heel had been secured by nails.

The screw 8 is driven in slantingly towards the 50 rear of the heel 7, into which a hole has previous- 55

ly been drilled for preventing it from splitting, but at a right angle to the plate 1. This draws the heel 7 firmly against the heel portion of the shoe, giving the union a strength several times greater than if effected by nails, and holding the heel 7 perfectly along its upper surface.

It will be apparent from the construction described, that it is an easy matter to loosen the screw 8 and to change the heels of the shoes for other heels, or to change the heel of one shoe 10 to the other. The front of the heel 7, commonly covered by a continuous strip from the under sole, is in these detachable heels separately covered by a strip 11. The heels 7 may be either 15 of wood, leather, metal or any other conventional material, and the shape of the screw 8 may be adapted for any of these materials.

What I claim is:

1. In a shoe with a removable heel, the combination of a heel plate placed on the heel portion of the insole of the shoe, said plate being relatively thick and having a concave upper surface following the curve of the heel of the foot, and a convex under side following the concavity 20 of the heel surface bearing against the shoe, a projection provided on the under side of said plate passing through holes in the outer and inner soles of the shoe, sharp-edged ribs extending 25 from the sides of said projection for embedding

themselves in the material surrounding one of said holes, and a screw passing through a countersunk hole in said projection and entering the heel.

2. In a shoe with a removable heel, the combination of a heel plate placed on the heel portion of the insole of said shoe, said plate having a concave upper surface following the curve of the heel of the foot, a convex lower surface following the concave shape of the heel surface adjacent to the shoe, said heel plate being relatively thick at the rear of the shoe and tapering from the rear portion towards the front portion, a conical projection provided on the under side of said plate and passing through holes in the outer and inner soles, said projection being of a length slightly less than the combined thickness of said outer and inner soles, sharp-edged ribs extending 10 downwardly along the sides of said projection and entering into the material surrounding one of 15 said holes, longitudinal and transverse sharp-edged ribs provided along the under side of said plate and embedding themselves in the insole, a screw passing through a countersunk hole in said projection and entering the heel, and a shank 20 stiffener gripped at its rear end with its rear end 25 between said plate and said heel.

GUILLERMO STAINES.
